UNITED STATES PATENT OFFICE.

EDWARD AUSTIN WILLIAMS, OF SAN FRANCISCO, CALIFORNIA.

DEVICE FOR LOWERING WINDOW-SASH.

1,290,451.

Specification of Letters Patent.

Patented Jan. 7, 1919.

Application filed June 22, 1917. Serial No. 176,341.

To all whom it may concern:

Be it known that I, EDWARD A. WILLIAMS, a citizen of the United States, residing at San Francisco, in the county of San Francisco, State of California, have invented a new and useful Device for Lowering Window-Sash; and I do hereby declare the following to be a full, clear, and exact description of the invention, such as will enable others skilled in the art to which it appertains to make and use the same.

The invention is a device for lowering the upper sash of a window and seeks to provide, as one of its objects a means for lowering such upper sash without the necessity of having to raise the lower sash to accomplish this.

Another object of the invention is to provide a cheap and efficient device designed for easily attaching to the window frame and having means connected with the sash, whereby the latter may be lowered or raised without having to interfere with the lower sash.

Other objects of the invention will appear from the detailed description which follows.

Two specific embodiments of the device are set forth in the accompanying drawings but to neither of these is the invention to be restricted. Reduction to practice may suggest certain changes or alterations and these the right is claimed to make, provided they be not incompatible with the spirit of the appended claim.

The same numerals of reference designate the same parts in all the figures of the drawings, wherein:

Figure 1 is a view of a portion of the window frame showing the invention attached.

Fig. 2 is a view showing the window frame and sash in section, showing the device in edge elevation.

Fig. 3 is a detailed perspective view of a portion of the sliding arm.

In the drawings, 1 represents a window frame having the upper sash 2 and the lower sash 3.

The device for raising and lowering the upper sash is contained on the side of the window frame, so that it may not obstruct the light from the window or appear unsightly from the outside. This embodiment comprises an eye 12 fixed in the top of the sash 2 at its center. An arm 13 engages

this eye, the arm terminating in an integral sleeve 14 which is adapted to slide over the rod 10. The rod 10 has an angled end through which protrudes a foot 15 by means of which the upper end of the rod is secured to the frame 1 with the aid of the screws 16. At the bottom of the rod 10 a bracket 17 is attached to the frame 1 by means of the screw 18. This bracket has an eye through which the rod 10 passes and in which it is secured by means of a set screw 19.

Where the rod 10 blends into its angled end 11, a grooved roller 20 is rotatively mounted, the roller being supported on the screw stud 21. An endless cord 22 passes over the roller 20 and extends down in the vicinity of the bracket 17, this cord being attached to the sleeve 14 by any suitable method of attaching it to the stud 23.

At either end of the sleeve 14 and on the diametrically opposite side from the arm 13, the stems 24 project. These stems have the forked end 25 in which the rollers 26 are rotatively mounted, these rollers being designed to bear upon the frame 1 and to prevent the sleeve 14 from binding on the rod 10 as it is drawn up and down the latter and offsetting the tendency of the pull of the sash 2 on the arm 13 to create this binding effect of the sleeve 14 on the rod 10.

It will be seen that by pulling on one side of the cord 22 the sleeve 14 is moved down the rod 10, carrying with it the arm 13 and lowering the sash 2 to which the arm 13 is connected. The pulley on the other side of the cord 22 reverses this operation and of course raises the sash 2.

In applying the embodiment shown in Fig. 3, it is essential that the eye 12 be in the center of the sash, so that the pull thereon will be in the center. The device is capable of attachment to windows of various widths, because of the fact that the eye 12 and arm 13 are not rigidly connected together. The eye 12 can always be placed in the center of the sash and the arm made to engage it by placing the end of the arm in the eye, the distance which the arm will project beyond the eye being determined by the width of the window to which the device is applied.

The screw eyes or any other acceptable means permitting a cord to be drawn through them may be used in place of the rollers

shown and wire ropes or chains may be used in place of the cord shown without departing from the spirit of the appended claim.

What is claimed is:

- 5 In a device as set forth, the combination with an upper window sash mounted in a window frame, of an eye on the front face of the upper rail of the sash substantially midway between the end of said rail, a pair 10 of brackets secured to the inner part of one side of the frame, one above the other, a guide rod mounted in said brackets, a bracket arm disposed horizontally in parallelism with the face of said upper sash and having 15 a cylindrical part loosely engaging through said eye, said bracket arm extending in a direction from the eye toward the side of the window frame and provided with a depending laterally extending portion terminating in an elongated sleeve, through 20 which the guide rod vertically engages, said sleeve owing to the depending portion being below and to one side of the horizontal part

of the bracket arm, a pulley mounted on the upper bracket, a loop cord passing over the pulley and having one side of the loop attached to the sleeve, whereby a pulling action on either side of the loop cord may act to lower or raise said sash, a pair of stems, one adjacent each end of the sleeve and forming an integral part therewith and extending laterally at right angles to the sleeve and toward the inner face of the window frame, and rollers mounted on the ends of said stems and engaging the inner face of the window 30 frame, to assist in guiding the sleeve and preventing angular binding of the sleeve on the guide rod.

In testimony whereof I have signed my name to this specification in the presence of 40 two subscribing witnesses.

EDWARD AUSTIN WILLIAMS.
